RAT GUARDS

George A. Reubenstine, 162 Adelphi St., Brooklyn, N.Y.

Filed Oct. 6, 1959, Ser. No. 844,659

10 Claims. (Cl. 114—221)

The present invention relates to an improved rat guard and more particularly to the type which is applied to ships' hawsers, cables and lines.

The principal object of this invention is to provide a novel and improved rat guard which is easily and effectively mounted onto a hawser, easily removed therefrom and which is light in weight.

Another object thereof is to provide a novel and improved rat guard construction in which a means is automatically operated to securely engage the hawser when the guard is closed around it, and said guard is automatically opened when said engagement means is withdrawn from said hawser.

Still a further object of this invention is to provide a novel and improved rat guard of the character described, which is reasonable in cost, easy to manipulate, convenient for storage when not in use and efficient in carrying out the purpose for which it is designed.

Other objects and advantages will become apparent as this disclosure proceeds.

For one practice of this invention, its embodiment may be described as comprising a disc in upright plane provided with a downwardly opening radial notch through which the hawser lies. Sector-shaped doors positioned against one face of the disc, are swingably mounted thereon; each in normal rest position covering substantially a lower quarter of said disc and closing said notch, leaving only a hole through which the hawser is positioned fitted therein. On the upper part of said disc, there is an uprightly positioned, elongated bolt provided at its lower end with a point formation adapted to enter into and engage the hawser. Each door is linked to said bolt so that upon raising the bolt, said doors will be automatically swung upwardly and open the notch. From such position, upon release of the bolt, the doors will swing downwardly due to their response to gravity and draw the bolt downwardly. Said bolt at its upper end carries a swingably mounted handle rod which can be swung upward to substantially horizontal position for manipulation from ship side and is used to further push the bolt downward or to lift the bolt. Upon upward movement of the bolt, the doors are automatically opened to release the guard for removal. The fall of the doors, automatically brings the bolt into engagement with the hawser. The disc and its doors may be of sheet metal properly weighted if necessary. The doors when closed, are preferably in overlapping relation.

I will now give a detailed description of a preferred embodiment of this invention, for which I will refer to the accompanying drawing which is part of this specification. In this drawing, similar characters of reference indicate corresponding parts in all the views.

Fig. 1 is a front view of a rat guard embodying the teachings of this invention. Here the doors are open.

Fig. 2 is a side or end view of Fig. 1, showing it set on a hawser. Here, the guard is shown complete with the mentioned swingable handle rod, which is omitted in Fig. 1 to attain clarity of illustration.

Fig. 3 is a front view like Fig. 1, but of a slightly modified construction. Here, the guard is engaged on the hawser. The doors are closed.

Fig. 4 is a fragmentary section taken at line 4—4 in Fig. 3.

Fig. 5, drawn to a reduced scale, is a front view of another embodiment where only one door is employed. This view only shows the disc and its single door in closed position thereon. The moved position of said door is also indicated.

Fig. 6, also drawn to a reduced scale, is a fragmentary front view of another modification.

In the drawing, the rat guard indicated generally by the numeral 15 in Fig. 1, comprises a plate or disc 16, provided along its vertical diameter with an elongated hawser-engagement bolt 17 which is slidably engaged in the channel track 18 along the upper part of said diameter, while said disc, in its lower part along said diameter, is provided with a parallel-sided, downwardly-opening notch 19, whose upper closed edge 19' is a concave half circle concentric with the disc perimeter. This notch is for holding the hawser 20 therethrough. The numerals 21, 22 indicate flat sector-shaped doors which are swingably mounted to said disc at 23 and 24 respectively and preferably lie against one surface of such disc. At normal rest position, said doors overlap each other and cover the notch 19, except for the hole formed by the edge 19' and the notches 21', 22', through which hole the hawser 20 lies, and the bolt 17 is partially across such hole, where said bolt presents its pointed lower end 17' which imbeds itself into the hawser body. Such normal rest condition of said components is illustrated in Fig. 3. Since it is required that upon raising the bolt 17, that the doors 21, 22 shall swing upwardly to their position shown in Fig. 1, said doors are linked to the bolt by either the flexible cables 23, 24 or the rigid links 23', 24' respectively. Stops 25, 26 are secured on the disc 16, to limit the upward movement of the doors 21, 22. At the top of the bolt 17, a handle rod 27 is swingably linked and has attached thereto the rope 28, whose free end is accessible aboard ship so that the handle rod 27 can be raised for manipulation from aboard ship. In normal rest position, said handle rod hangs downward.

The rat guard is applied onto the hawser 20, from aboard ship. Holding handle 27 in hand, the flat clear surface 16' of the disc plate 16 faces the land and the disc assumes vertical position. The weight of the disc causes it to fall until the doors 21, 22 are halted by the stops 25, 26 respectively. The notch 19 is now clear, so the rat guard is moved to receive the hawser 20 therein. The above described condition is shown in Fig. 1. Now, handle 27 is moved downward after the disc has come to rest on the hawser. The weight of the doors will cause them to swing downward to closed position, pulling the bolt 17 downward into engagement with the hawser 20. The handle 27 is then moved to further push the bolt's engagement point 17' deeper into the hawser; the handle being directly connected to said bolt 17. The rat guard is now mounted as shown in Fig. 3. The handle 27 is let to fall, but the rope 28 attached thereto is secured aboard ship so that the handle 27 can be lifted for manipulation to release the rat guard for removal, when desired. It is suggested that the meeting edges of the doors shall be in overlapped relation as at 29 when in closed position.

As a modified embodiment, as shown in part in Fig. 5, all of Fig. 1 shall be deemed included, except that only one door 30 is employed in place of the twin doors 21, 22, and hence elements 23 and 25 are also omitted. Here in Fig. 5, the single door 30 is of sufficient dimension to cover and retracts to position 30' to be in open position.

In the modified structure shown in Fig. 6, the bolt 30 is longitudinally slideable and axially rotatable in the track 18'. The piece 32 for attachment of linkage to the doors (not shown here), is swivelly mounted at the upper end of the bolt 30, by being rotatable on the headed axis element 33 which is pinned to said bolt at 34. The track 18' is provided with a slanted slot 31, in which slidably fits the pin 35; the latter extending laterally from said bolt 30. The length of this slot is such that upon downward movement of the bolt 30, such 10 bolt would be given a part turn, to drill itself into the hawser 20. This feature can be used in the different embodiments shown in the drawing.

The rat guards shown may be hung up when not in use, for which purpose the hole 31 is provided in the 15 disc 16. The disc and doors may be of sheet metal, plate or other suitable materials.

This invention is capable of numerous forms and various applications without departing from the essential features herein disclosed. It is therefore intended and desired that the embodiments shown herein shall be deemed merely illustrative and not restrictive and that the patent shall cover all patentable novelty herein set forth; reference being had to the following claims rather than to the specific description herein to indicate the 20 scope of this invention.

I claim:

1. In a rat guard of the character described, a main plate member having an elongated notch to receive a hawser therethrough to lie against the closed end of said notch, a hawser-engaging bolt slidably mounted on said main plate member, normally in position to engage the hawser, door structure swingably mounted on the main plate member, normally in position to substantially cover all of said notch which is unoccupied by the hawser and means linking said bolt and door structure whereby on movement of said bolt away from the hawser position through said notch, the door structure will be automatically swung to a position to uncover the notch.

2. A rat guard as defined in claim 1, wherein the door structure is a plate against the main plate member and wherein the means linking said door plate to the bolt is an elongated pliable member which is secured at its respective ends to said bolt and door plate.

3. A rat guard as defined in claim 1, wherein the door structure is a plate against the main plate member and wherein the means linking said door plate to the bolt is a rigid link pivotally attached at its respective ends to said bolt and door plate.

4. A rat guard as defined in claim 1, wherein the door structure comprises two plates positioned against the main plate member, one to each side of the notch respectively and wherein the linking means comprises two elongated pliable members secured at one of their respective ends to the bolt and at their other ends to said door plates respectively.

5. A rat guard as defined in claim 1, wherein the door structure comprises two plates positioned against the main plate member, one to each side of the notch respectively and wherein the linking means comprises two links secured at one of their respective ends to the bolt in pivotal relation therewith and pivotally secured at their other ends to said door plates respectively.

6. A rat guard as defined in claim 1, wherein the door structure comprises two plates positioned against the main plate member; the edge portion of one of the door plates which is over the notch in the normal condition of the rat guard, being off-set from the plane of the door plate it is on, whereby in said normal condition, said door plates overlap across the notch in the main plate member.

7. A rat guard as defined in claim 1, wherein the bolt is also rotatable on the main plate member for rotary movement about an axis line through said bolt which is parallel to its line of sliding movement and wherein an element carried by the plate is provided with an elongated slot which is slanted in relation to said sliding line of movement and including a pin extending laterally from the bolt into said slot and engaged in said slot for sliding movement therealong, whereby on sliding movement of said bolt on the main plate member, the bolt will be automatically given a rotary movement; the position and length of said slot being such that such rotary movement of the bolt occurs when the bolt is sliding and is in the space occupied by the hawser through the notch in the main plate member.

8. A rat guard as defined in claim 1, including an elongated rigid handle member pivotally connected to the bolt.

9. A rat guard as defined in claim 1, wherein the bolt, the door structure and the linking means therefor are at one surface of the main plate member.

10. A rat guard as defined in claim 1, wherein the axis of swing of the door structure is perpendicular to the main plate member.
